UNITED STATES PATENT OFFICE

157,020

VACUUM PACKAGING MACHINE

Willy E. Zimmermann, Chicago, Ill., assignor to
Standard Cap and Seal Corporation, Chicago,
Ill., a corporation of Virginia

Application March 15, 1947, Serial No. 137,615

Term of patent 3½ years

(Cl. D55—1)

To all whom it may concern:

Be it known that I, Willy E. Zimmermann, a citizen of the United States, residing at Chicago, county of Cook, and State of Illinois, have invented a new, original, and ornamental Design for a Vacuum Packaging Machine, of which the following is a specification, reference being had to the accompanying drawings, forming part thereof.

In the drawing,

Figure 1 is a front perspective view of a vacuum packaging machine showing my new design;

Figure 2 is a side perspective view of the vacuum packaging machine shown in Figure 1; and

Figure 3 is a perspective view of the other side thereof. The rear, not shown, is substantially like the front shown in Figure 1, except for the sealing housing which is plain.

I claim:

The ornamental design for a vacuum packaging machine, substantially as shown and described.

WILLY E. ZIMMERMANN.
